UNITED STATES PATENT OFFICE.

JOHN S. GARVIN, OF NEW YORK, N. Y., ASSIGNOR TO WESTERN ELECTRIC COMPANY,
INCORPORATED, OF NEW YORK, N. Y., A CORPORATION OF NEW YORK.

ENERGIZING CIRCUITS FOR VACUUM TUBES.

Application filed December 18, 1920. Serial No. 431,536.

This invention relates to energizing circuits for vacuum tubes of the type having an anode and an electrically heated cathode, an object of the invention being to supply cathode heating current and space current for such a vacuum tube from non-adjustable sources of voltage. A further object is to obtain relatively high voltage space current and relatively low voltage cathode heating current from two electromotive forces each of which is too high for application to the cathode and too low to properly supply the space current.

A further object of the invention is to obtain the requisite low and high voltage cathode and space currents of a vacuum tube amplifier, and also a potential difference between the cathode and the control electrode of the amplifier, from two electromotive forces each of which is too high for application to the cathode and too low to properly supply the space current.

The system of this invention is especially useful on battle-ships, where the source of supply is a 120 and 240 volt dynamo. In accordance with the invention, such a source may be used to energize an amplifier in such a manner that no battery is required, even though an electromotive force of 120 volts is too low for the plate circuit and too high to be applied to the filament. However, the system of the invention is capable of various other applications.

Fig. 1 of the accompanying drawing is a diagram of an embodiment of the invention in which the sources of electromotive force are indicated as batteries. Fig. 2 of the drawing shows diagrammatically another embodiment of the invention, the source of supply being three-wire dynamo-electric generating apparatus.

In Fig. 1, vacuum tubes are connected in parallel. An input transformer for the tubes is shown at 6, and an output transformer at 7. An adjustable by-pass for the tubes is indicated at 9. The plate circuit of each of the tubes is from a battery 10 through a lead 11, through the primary winding of the output transformer 7, to the anode of the tube, through the tube to the cathode, through lead 12 including a resistance 13, through a battery 15 and a lead 16 back to the battery 10. The filament of each of the tubes is heated by current passing from the battery 15 through a lead 17, in

cluding a resistance 18, through the filament of the tube, through the lead 12 including the resistance 13, and back to the battery 15.

In this system the electromotive force of each of the batteries 10 and 15 may be, for instance, of the order of 120 volts, even though such voltage is too high to be applied to the filament and too low to properly supply the space current for the tube. For the voltage drop in the resistance 18 due to the filament heating currents from the battery 15, plus the electromotive force of the battery 10, is the electromotive force applied across the anode and the high potential end of the filament, and the difference between the electromotive force of the battery 15 and the sum of the voltage drops in resistances 18 and 13 due to the filament heating currents in these resistances is the electromotive force applied to the filament. The voltage drop in 13 due to the space currents is of course negligible.

The resistance of 13 is determined by the value of the currents necessary to heat all of the filaments and the value of the negative potential desired on the grids. For the negative potential applied to the grids will be equal to the voltage drop in 13 due to the filament heating currents from the battery 15. The total filament heating currents may be, for instance, of the order of 10 amperes and the negative potential on the grids may be of the order of 25 volts. Then the resistance 13 will be 2.5 ohms. It will then be necessary to make the resistance of 18 of such a value that the electromotive force of the battery 15 divided by the sum of the resistance of 18, the resistance of the heated filaments in parallel and the resistance of 13 will be equal to the desired total filament heating current. That is, the electromotive force of the battery 15 minus the drop across the filaments must be equal to the sum of the drops in 13 and 18. The drop across the filaments may be, for instance, 8 volts. Therefore, with the specific values assumed for the filament current and drop, the negative grid potential, and the voltage of battery 15, the drop in 18 will be about $120 - (25 + 8) = 87$ volts. Therefore the voltage applied across the anode and high potential end of the cathode of each tube is $120 + 87 = 207$ volts, which is ample.

In Figure 2 the source of supply is shown by way of example as a three-wire system

- comprising dynamos 20 and 25 instead of the batteries 10 and 15 of Fig. 1. Moreover in Fig. 2 there is no resistance connected between the negative pole of the dynamo 5 and the filament, for obtaining a negative grid potential; and instead of a resistance common to the tubes 5 for obtaining sufficiently low voltage for the filaments and sufficiently high voltage for application 10 across the anodes and filaments, resistances 28 individual to the tubes are used. The plate circuit of each of the tubes 5 is from the dynamo 20 through a lead 11, through the primary winding of the output transformer 7 to the anode of the tube, through the tube to the cathode, through lead 12, through the dynamo 25 and back to the dynamo 20. The filament of each of the tubes 5 is heated by current passing from 15 the generator 25 through the lead 17 including the resistance 28 individual to the tube, through the filaments of the tube, and through the lead 12 back to the dynamo 25. Additional tubes 35 are shown as connected 20 in parallel with each other, transformer 7 serving as an input transformer for these tubes and a transformer 40 serving as an output transformer. The dynamos 20 and 25 supply the space current and the filament heating current for tubes 35. The plate circuit of each of the tubes 35 is from the dynamo 20 through a lead 51, through the primary winding of the output transformer 40 to the anode of the tube, through 25 the tube to the cathode, through a lead 52, the lead 12, and the dynamo 25 back to the dynamo 20. The filament of each of the tubes 35 is heated by current passing from the generator 25 through the lead 17, through a lead 57 including a resistance 48 individual to the tube, through the filament of the tube, and through leads 52 and 12 back to the dynamo 25. Resistances 48 perform the same function 30 in connection with these tubes that resistances 28 perform in connection with tubes 5. That is, because of the drops due to filament heating currents in 28 and 48, the electromotive forces applied to the filaments of tubes 5 and 35 are substantially lower than the electromotive force of the dynamo 25, and the electromotive force applied across the anode and the filament of each of the tubes 5 and 35 is substantially 35 higher than the electromotive force of the dynamo 20. The dynamos 20 and 25 are intended to represent any well known type of three-wire dynamo-electric generating apparatus.
- 60 What is claimed is:
1. A vacuum tube having an anode and having a cathode adapted to be electrically heated, two sources of electromotive force, the voltage of each of said sources being too high for application to said cathode and
- too low to properly supply space current for said tube, and means connected between said sources and said tube for applying to said cathode an electromotive force derived from one of said sources but substantially lower 70 than the electromotive force of either source and impressing between the anode and the cathode an electromotive force derived from said sources and substantially higher than the electromotive force of either source and 75 lower than the electromotive force of the combined sources.
2. A vacuum tube having an anode and having a cathode adapted to be electrically heated, said cathode having two terminals, 80 and means for supplying electromotive force to said tube, said means comprising a source having its positive pole connected to said anode, a source having its negative terminal connected to one of said terminals, and a lead including a resistor connecting the other poles of said sources to the other of said two terminals, said resistor being of such value as to materially increase the electromotive force between said anode and 85 said other terminal.
3. A vacuum tube having an anode, a cathode adapted to be electrically heated and a control electrode, two sources of electromotive force, means connected between 90 said sources and said tube for applying to said cathode an electromotive force substantially lower than the electromotive force of either source and impressing between the anode and the cathode an electromotive 100 force substantially higher than the electromotive force of either source and lower than the electromotive force of the combined sources, said means comprising a resistor, and a connection from said resistor to said control electrode for impressing upon said electrode a negative potential derived from the drop in said resistor.
4. A vacuum tube comprising an anode, a cathode having two terminals and adapted 110 to be electrically heated and a control electrode, a source of electromotive force having two terminals at different potentials and having a third terminal at a potential between the potentials of said two terminals, 115 means comprising a resistor connecting said two terminals across said anode and one of said cathode terminals, and an impedance connected between said third terminal and the other of said cathode terminals, said impedance being of such value that the electromotive force supplied to said cathode is small in comparison to that across any two of the three terminals of said source, and a connection from said resistor to said control electrode, for impressing upon said electrode a negative potential derived from the drop in said resistor.
5. A vacuum tube having an anode and having a cathode adapted to be electrically 120

heated, two sources for heating the cathode and supplying space current for the tube, and means for connecting said sources to said tube and maintaining the point of highest potential on the cathode at a potential lower than the lowest potential of one of said sources by an amount equal to a large portion of the voltage of said source, said means including a resistance element in the space current path of said tube.

6. A vacuum tube having an anode, a cathode adapted to be electrically heated and a control electrode, two sources for supplying electromotive force for heating said cathode, sending space current through said tube and charging said control electrode, and means including resistors for connecting said sources to said anode, cathode and control electrode, maintaining the point of highest potential on said cathode at a potential lower than the lowest potential of one of said sources by an amount equal to a large portion of the voltage of said source and maintaining said control electrode at a potential lower than the point of lowest potential on said cathode.

7. A vacuum tube having an anode and having a cathode with two terminals, a current generator having two terminals at different potentials and a third terminal at a potential between the potentials of said two terminals, leads from said two generator terminals to said anode and one terminal of said cathode, respectively, and a lead including a resistor connecting said third generator terminal with the other cathode terminal, said resistor being of such value that the voltage across said cathode is small in comparison to the voltage between said third

terminal and either of said two generator terminals and the voltage between the anode and said other cathode terminal is equal to the voltage between said anode and said third terminal plus a large portion of the voltage between said third terminal and said one cathode terminal.

8. In combination, a plurality of space discharge devices, each having a cathode adapted to be heated and an anode, a common source of space current for said devices and a common source of cathode heating current, said cathodes being connected in parallel across said common source of heating current, parallel connections from the separate anodes to said common source of space current and a resistance common to the cathode heating and anode circuits of all of said devices.

9. In combination, a plurality of space discharge devices, each having a cathode adapted to be heated and an anode, a common source of space current for said devices and a common source of cathode heating current, said cathode being connected in parallel across said common source of heating current, parallel connections from the separate anodes to said common source of space current, and resistance means common to the cathode heating circuit and the space current circuit of each of said devices of such magnitude that the potential drop therethrough comprises a large part of the voltage of said heating current source.

In witness whereof, I hereunto subscribe my name this 16th day of December, A. D., 1920.

JOHN S. GARVIN.
